BENDING DIE

Nathan Kase, Brooklyn, and Louis Wiesenfeld,
New York, N. Y.

Application July 10, 1935, Serial No. 30,626

7 Claims. (Cl. 153—1)

This invention relates to improvements in bending dies.

In our Letters Patent No. 2,013,706 granted September 10, 1935 for Fastening device, there is disclosed a slide fastener for closing the entrance opening of a bag or like article, and the device consists generally of a plurality of clips joined together by a flexible element, the clips being bent into operative position about retaining beads on the walls of the opening in the article, one of the end clips being fixedly anchored to the beads while the remaining clips are slidably associated therewith. It is therefore the main object of this invention to provide a bending die which will simultaneously bend all of the clips about the beaded edges of the opening to be closed thereby, and which will bend one of the end clips a greater degree than the others to effect an anchoring of the same to the article on which the device is to be used.

Another feature of the invention resides in a clip bending die which includes positioning and supporting means for a row of clips to be bent, and tension means acting upon the clips to hold them seated preparatory to the bending operation.

A further feature of the invention is the provision of a bending die which includes a pair of coacting die members which when brought together, operate to bend a row of flexibly connected clips from a normally open position to a closed position, the die faces being such that a predetermined clip is more fully closed than the others to provide an anchor clip for the row or set of clips for captively connecting the fastening device to an article to be equipped therewith.

With these and other objects in view, the invention resides in the certain novel construction, combination and arrangement of parts, the essential features of which are hereinafter fully described, are particularly pointed out in the appended claims, and are illustrated in the accompanying drawing, in which:

Figure 1 is an end elevational view of the clip bending die, the parts being shown in closed position.

Figure 2 is a front elevational view.

Figure 3 is an enlarged vertical transverse sectional view on the line 3—3 of Figure 2, but showing the die member in open position in full lines and in closed position in dotted lines, the open end of a bag being fitted with the clip fastener also being shown in dotted lines.

Figure 4 is a vertical transverse sectional view

on the line 4—4 of Figure 2, but showing the die in partially closed position in full lines and in fully closed position in dotted lines, the open end of a bag being fitted with the clip fastener being shown in full lines.

Figure 5 is a collective perspective view of the coacting die members in separated condition.

Figure 6 is a perspective view of a bag equipped with the clip fastening device applied thereto by the use of the clip bending die, the clips being shown in closing position in full lines and in open position in dotted lines.

Figure 7 is a perspective view of one of the fastening clips per se.

In Figure 6 of the drawing, we have shown for illustrative purposes, the flexible bag 10 equipped with a slide clip fastening device 11 for closing the open top thereof. The fastening device 11 includes a plurality of substantially U-shaped clips 12, the free end of one of the legs of each clip being provided with an eye 13, the width of the eye being less than the width of the body portion of the clip. Passing through the eyes 13 is a flexible element in the form of a chain 14, the eyes tightly engaging the chain to secure the same thereto against sliding. The chain 14 is of a length approximating the length of the bag opening, and the clips are fixed thereto at spaced distances to be spread out the length of the opening to close the same as shown in full lines in Figure 6. The clips 12 are bent about a pair of beads 15—15 provided at the opposite edges of the bag opening and extending the length thereof, the beads lying in substantially the same plane when the bag opening is closed. One of the end clips 12 and further designated by the letter A constitutes an anchor clip and is more tightly bent about the beads to prevent sliding movement thereof and to captively connect the fastening device to the bag. The other clips 12 slide toward and away from the anchor clip A when moved to open and closed positions respectively. The construction so far described is shown in our Letters Patent No. 2,013,706 above referred to, and has been herein shown and described to more clearly set forth the purpose of our bending die, now to be described.

Each of the U-shaped clips 12 before bending are of a shape shown in Figure 7 and includes a bight portion B and a pair of outwardly diverging legs C and D. The eye 13 is formed on the free end of the leg D and this leg at its free end is bent inwardly at E, thus making the eye inwardly offset with respect to the leg D, and when the leg C is bent down toward the leg D, the

eye 13 and the leg C cooperate to provide a restricted entrance to the clip.

Our bending die includes a lower stationary die member 16 which is of substantially rectangular configuration and extending downwardly from the bottom thereof, is an attaching bolt 17 which passes through an opening 18 in a table or other like support 19, the threaded end of the bolt or stud 17 receiving a clamping nut 20 which bears against a washer 21 interposed between the nut and the underside of the table 19. Extending inwardly of the top of the die member 16 and opening at the front thereof is a channel 22 of a shape in cross section to conform to and receive the leg sides D of a plurality of clips 12. Thus the rear wall of the channel is curved as at 23 to receive the bight portions of the clips whereas the front of the channel terminates in an upstanding shoulder 24 on which the eyes 13 of the clips rest. The channel 22 and the shoulder 24 extend the full length of the die member and which length may be optional, depending upon the number of clips to be bent in a single operation.

25 Screwed into threaded sockets 25 which open onto the top side of the die member 16, are threaded studs 26, the outer ends having heads 27. Studs 26 freely pass through openings 28 provided in a plate 29, the front edge of the plate 30 overhanging the channel 22. Springs 30 are interposed between the plates 29 and the heads 27 of the respective studs for the purpose of placing a tension upon the plate for a purpose to be presently explained. It will be appreciated that this tension may be adjusted to any desired degree by turning the threaded stud 26 in either direction. One of the front corners of the plate 29 is cut away for a distance approximating the width of one of the clips to be bent and which cut away portion is designated at 31.

Superposed with respect to the lower stationary die member 16, is an upper movable die member 32, which is also of substantially rectangular configuration and from which an actuating stem 33 rises. The stem 33 may be operatively connected to any actuating mechanism for imparting an up and down sliding movement to the die member 32 with respect to the stationary die member 16. Any foot actuated means or electrically controlled means may be resorted to for operating the slideable die member 32. The die member 32 is provided with vertical openings 34 for freely receiving the upwardly extending portions of the threaded studs 26. The under side 55 of the die member 32 is provided with a downwardly extending rib 35 which extends the length of the die member and is disposed in vertical alignment with the front portion of the channel 22 of the lower die member 16. It is this rib 60 35 which serves to press a row of clips to be bent with the exception of the end anchor clip, and for the purpose of bending the anchor clip a greater degree than the other clips, there is provided a screw 36 which is threaded downwardly 65 through an opening 37 in the die member 32, the inner end of the screw being disposed outwardly beyond the plane of the rib 35 as best seen in Figure 3 of the drawing. The screw 36 may be held in an adjusted position by a nut 38 which 70 is threaded thereto and bears against the top of the die member 32. It is of course understood that the screw 36 is provided with a head 39, the same having a kerf 40 to facilitate the insertion of a screw driver to impart turning movement to the screw to effect an adjustment. The

75 screw 36 is located at one end of the die member 32 and upon downward movement of the said die member, the depending end of the screw clears the plate 29 by reason of the cut away portion 31.

In the operation of the die, a plurality of clips 12 joined by the chain 14 are respectively placed in the channel 22 of the stationary die member 16 as illustrated in Figure 5. The clips 12 are bunched together one against the other and one of the end clips is disposed beneath the cut away portion 31 of the plate 29. When the clips are placed in the channel 22, the upwardly extending legs C are engaged by the front edge of the plate 29 and by reason of the spring tension upon the plate, a corresponding tension is placed upon the clips to maintain them in seated position. It is possible to position the bodies of the clips one against the other by reason of the fact that the eyes 13 are of a less width to permit of portions of the chain between the clips to depend downwardly in loop formation, the front of the stationary die member 16 below the shoulder 24 being cut away as at 41 to accommodate the looped portions of the chain. With the clips positioned in the stationary die member as just described, the beaded end of the bag 10 is inserted into the clips as shown in dotted lines in Figure 3 and in full lines in Figure 4. The beads 15-15 are received within the clips between the bight portions B and the offset eye 13, with the body 30 of the bag extending outwardly from the die. Upon operation of the actuating means, the upper movable die member 32 moves downwardly, and in so doing the rib 35 engages the free ends of the legs C of the clips, excepting the end anchor clip A, and bends the legs to a substantially horizontal position as shown in dotted lines in Figure 4. Simultaneously with the engagement of the rib 35 with all the clips excepting the anchor clip, the depending end of the screw 36 strikes 35 the end anchor clip A and presses the leg C into tight engagement with the open end of the bag 10. In order to effect an absolute tight clamping between the eye 13 of the anchor clip A and the leg C, the end of the screw 36 may slightly deform the body of the clip as shown in dotted lines in Figure 3. After the bending operation, the actuating means may be operated to effect an upward movement of the upper die 32, whereupon the bag 10 may be withdrawn from the die with the clips in fastened position thereon, and which produces a closure fastener of the type shown in Figure 6 of the drawing.

While we have shown and described what we consider to be the most practical embodiment of our invention, we wish it to be understood that various changes in construction as come within the scope of the appended claims may be resorted to if desired.

Having thus described the invention, what we claim as new and desire to secure by Letters Patent of the United States, is:—

1. A slide fastener bending die for the purpose of bending the legs of a plurality of loosely connected substantially open U-shaped clips together about a pair of meeting beaded edges of an article to be equipped with such slide fastener comprising a pair of coacting die members, one movable relative to the other, means on one of the die members for seating thereon a row of clips to be bent, resilient holding means engageable with the seated clips to prevent accidental movement thereof, and means on the other of said die members engageable with clips for effecting bending of the same to a substantially closed position.

2. A slide fastener bending die for the purpose of bending the legs of a plurality of loosely connected substantially open U-shaped clips together about a pair of meeting beaded edges of an article to be equipped with such slide fasteners comprising a lower stationary die member, means on said stationary die member for seating and holding a row of clips to be bent, an upper vertical movable die member, and means on the upper die member engageable with the clips upon downward movement thereof to cause a simultaneous bending of the clips to a substantially closed position, and effecting a greater bending of one of the clips than that imparted to the others.

5 15 3. A slide fastener bending die for the purpose described comprising a pair of complementary superposed die members, a seat extending lengthwise of the lower of said die members for receiving the work to be bent, a spring actuated plate 20 overlying said seat for resiliently holding the work upon said seat, and a pressing rib extending downwardly from the upper die member above said seat, and clear of the plane of said plate.

25 4. A slide fastener bending die for the purpose of bending a plurality of loosely connected substantially open U-shaped clips to substantially closed position about a pair of meeting beaded edges comprising a lower stationary die member having a channel extending lengthwise thereof 30 for the seating of the clips to be bent, an upper vertically slidable die member including a rib depending from the bottom thereof for pressing engagement with the upstanding legs of the clips, and a bending element carried by said upper 35 movable die member and extending below the plane of said rib for bending one of the clips a greater degree than the others.

40 5. A slide fastener bending die for the purpose of bending a plurality of loosely connected substantially open U-shaped clips to substantially closed position about a pair of meeting beaded edges comprising a lower stationary die member having a channel extending lengthwise thereof 45 for the seating of the clips to be bent, an upper vertically slidable die member including a rib depending from the bottom thereof for pressing

engagement with the upstanding legs of the clips, and an adjustable bending element carried by said upper movable die member and extending below the plane of said rib for bending one of the clips a greater degree than the others.

5 10 6. A slide fastener bending die for the purpose of bending a plurality of loosely connected substantially open U-shaped clips to substantially closed position about a pair of meeting beaded edges comprising a lower stationary die member 15 having a channel extending lengthwise thereof for the seating of the clips to be bent, a spring pressed plate carried by said stationary die member and overlying said channel for holding the clips seated therein, an upper vertically slidable 20 die member including a rib depending from the bottom thereof for pressing engagement with the upstanding legs of the clips, and a bending element carried by said upper movable die member and extending below the plane of said rib 25 for bending one of the clips a greater degree than the others.

7. A slide fastener bending die for the purpose described comprising a lower elongated stationary die member having a channel extending 25 lengthwise thereof for receiving a plurality of loosely connected substantially U-shaped fastener elements to be bent, a pair of headed posts rising upwardly from said stationary die member, a holding plate slidably mounted upon said posts 30 and having one longitudinal edge overhanging said channel, springs surrounding said headed posts and interposed between said plate and the heads of said headed posts, and an upper vertically slidable die member including a rib depending from the bottom thereof and disposed directly above said channel but clear of the plane 35 of the overhanging edge of said holding plate for direct pressing engagement with one leg of the U-shaped fastener element to be bent when the 40 upper die member is moved downward to bending position relative to the lower stationary die member.

NATHAN KASE.
